UNITED STATES PATENT OFFICE.

ALFRED PLANT, OF KEYPORT, NEW JERSEY.

DESIGN FOR A TILE.

SPECIFICATION forming part of Design No. 36,089, dated September 30, 1902.

Application filed August 11, 1902. Serial No. 119,357. Term of patent 7 years.

To all whom it may concern:

Be it known that I, ALFRED PLANT, a citizen of the United States, residing at Keyport, in the county of Monmouth and State of New Jersey, have invented a certain new, original, and ornamental Design for a Tile, of which the following is a specification.

This invention relates to tiles; and it consists in a new, original, and ornamental design for the same, as shown in the accompanying drawings, in which—

Figure 1 is plan view, and Fig. 2 a cross-section.

My newly-designed tile is substantially hexagonal in shape; but two opposite sides 1 of the hexagon are longer than the other four 2, which are all equal. The face 3 of the tile is flat, but bears a figure in low relief, said figure being symmetrical with reference to

the longer and shorter axes of the tile. The 20 figure has semicircular ends 4, adjacent to which are rounded lateral enlargements 5, connected by slightly-concave lines 6 with a narrow middle portion 7, on each side of which is a slight rounded projection 8. The 25 face 9 of the figure is flat, and the edges are slightly beveled.

Having thus described my invention, what I claim is—

The ornamental design for a tile, substantially as herein shown and described.

In witness whereof I have hereunto set my hand this 7th day of August, 1902.

ALFRED PLANT.
